UNITED STATES PATENT OFFICE.

GUSTAF A. WALLIN, OF NEW YORK, N. Y., ASSIGNOR TO A. KIMBALL COMPANY, OF NEW YORK, N. Y., A CORPORATION OF NEW YORK.

PINLESS MARKING-TICKET.

1,073,828.

Specification of Letters Patent. Patented Sept. 23, 1913.

Application filed January 5, 1910. Serial No. 536,445.

To all whom it may concern:

Be it known that I, GUSTAF A. WALLIN, a subject of the King of Sweden, and resident of New York, county of New York, 5 State of New York, have invented an Improvement in Pinless Marking-Tickets, of which the following description, in connection with the accompanying drawing, is a specification, like characters on the drawing 10 representing like parts.

This invention has for its object the production of a novel and efficient marking ticket which can be easily and securely attached, without the use of pins or other 15 similar devices, to narrow fabrics such as webbing, ribbon, neck-scarfs, suspenders and the like, and by preference such pinless ticket is so constructed as to adapt it to standard articles by simple and most effective means.

In accordance with my invention the ticket comprises an elongated blank formed of a plurality of plies of non-metallic, flexible material provided with transverse 25 grooves on one face thereof and opposed permanently expanded portions on the opposite face, a non-elastic metallic stiffener being located between and concealed by the plies and extending substantially the length 30 thereof and bridging or crossing said grooves. The transverse grooves are by preference at proper distances apart to accommodate or substantially correspond to the width of the particular article to which the 35 ticket is to be applied, thereby providing not only a clear and accurate predetermined guide for the folding of the ticket when applied, but also facilitating such folding or bending and at the same time defining 40 the limits of the display portion of the ticket. The opposed permanently expanded portions on the opposite face of the ticket enable the latter to be bent or folded on the transverse grooves without cracking or 45 breaking the exposed surface of the ticket, thereby materially increasing its durability and enhancing its appearance.

The display portion of the ticket presents a smooth and flat surface upon which can

be printed or otherwise marked the name 50 of the maker of the fabric, its cost, and such other information as may be desired, the entire display portion being exposed to view when the ticket is applied to the fabric.

When applied the ticket embraces and is 55 frictionally held in place upon the fabric without the use of pins, staples, or other fastening means which enter or penetrate the fabric, the application and removal of the ticket being effected easily and rapidly 60 without possibility of the slightest injury to the most delicate fabric.

In the accompanying drawings, Figure 1 is a plan view of a pinless marking ticket embodying one form of my invention, as the 65 ticket appears when laid out flat, showing the display face thereof; Fig. 2 is a longitudinal section taken on the line 2—2, Fig. 1; Fig. 3 is a view similar to Fig. 1 and of a modified form of the ticket; Fig. 4 is 70 a longitudinal section thereof on the line 4—4, Fig. 3; Fig. 5 is a rear view of the ticket illustrated in Fig. 1 applied to a fabric, showing the attaching portions of the ticket bent or folded over upon and to embrace the fabric; Fig. 6 is a similar view 75 of the ticket shown in Fig. 3; Fig. 7 is a rear view, on a smaller scale, of the ticket illustrated in Fig. 3.

In practice the ticket comprises an elongated blank made up or formed of a plurality of superimposed plies 1, 2, Fig. 1, of non-metallic, flexible material such as heavy paper or thin card-board, glued or cemented together.

The body or display portion of the ticket is shown at 3, and the foldable attaching portions or flaps 4, 5 are located at opposite ends thereof, and between the display portion and the said attaching portions the 90 ticket is provided with transverse grooves 6, 6 on one face thereof, to wit, the back or under face, and with opposed permanently expanded portions 6^x, 6^x on the opposite front or outer face thereof.

A non-elastic, metallic stiffener is located between and concealed by the plies and extends the length thereof, and in the form of

ticket illustrated the stiffener is shown as two wires 7, 7, arranged in parallelism near the longitudinal edges of the ticket and bridging or crossing said grooves.

5 In the sectional view of the ticket, Fig. 2, the stiffener is shown as bent at 7^x, where it bridges the grooves 6, 6, but such bending of the stiffener may be omitted, as shown in Fig. 4, wherein the stiffener is a single 10 wire 7', and in such case the transverse grooves may stop short of the stiffener at opposite sides thereof.

The transverse grooves 6 provide a clear and accurate predetermined guide for the 15 bending or folding over of the attaching portions 4, 5 of the ticket when applying the same to a fabric, and as they are formed on the back or under face of the ticket said grooves facilitate the bending and folding 20 over by accommodating the material of the plies crowded together by such bending, while by their position they clearly and distinctly define the ends of the display portion 3.

25 The bends in the ticket embrace and pinch the sides or edges of the fabric to which the ticket is applied, the bends being retained by the non-elastic stiffener, which also maintains the attaching portions 4, 5 pressed 30 firmly against the adjacent face of the fabric, as shown in Figs. 5 and 6.

35 Preferably the attaching portions or flaps 4, 5 are in their combined length somewhat shorter than the length of the body or display portion 3, as they will then lie flat and smooth and in substantial alignment upon the back of the fabric, but if desired such flaps may be made long enough for one to overlap the other.

40 The transverse permanently expanded portions 6^x on the outer or front face of the ticket, opposed to the grooves 6, insure a smooth and unbroken surface when the ticket is bent to be applied to a fabric, obviating any cracking or breaking of the face 45 of the ticket and hence increasing not only its strength and durability but enhancing its appearance. Such permanently expanded portions provide the necessary 50 amount of material to extend around the embraced edges of the fabric at the outer or convex sides of the bends made in the ticket, as will be apparent.

To apply the ticket the display portion 3 55 is laid across the face of the web or strip of fabric 8, Figs. 5 and 6, and the flaps 4, 5 are bent or folded over and turned down firmly upon and against the back of the fabric, and retained thereupon by the non- 60 elastic metallic stiffener, the pinching action of the stiffener wire or wires retaining the ticket firmly in place upon the fabric by frictional engagement therewith. By

bending out the flaps 4 and 5 the ticket can be detached instantly and without difficulty 65 from the fabric.

In the form of ticket illustrated in Figs. 3, 4, 6 and 7 the stiffener is shown as a single wire 7', extended centrally of the ticket, and bridging or crossing the transverse grooves 6, 6, said stiffener being shown as without bends, but the general features of the ticket as to the transverse grooves and the opposed permanently expanded portions 6^x are the same as heretofore described 75 in connection with Figs. 1, 2 and 5.

While it is by no means necessary to separate the transverse grooves a distance substantially equal to the width of the fabric to be marked it is often convenient to do 80 so, particularly when such fabrics have a standard width, as by such construction of the ticket it fits the fabric snugly and neatly and in a very attractive manner.

The transverse grooves form lines of least 85 resistance on which the ticket is bent, and the bends naturally follow or extend naturally along such lines when the ticket is applied to a fabric, so that the ends or flaps turn over upon the fabric in line with each 90 other and with the body or display portion, this feature being especially desirable in tickets provided with stiffening means as herein set forth.

Various changes or modifications may be 95 made by those skilled in the art without departing from the spirit and scope of my invention as set forth in the claims annexed hereto.

Having fully described my invention, 100 what I claim as new and desire to secure by Letters Patent is:—

1. As an article of manufacture a marking ticket comprising an elongated blank 105 formed of a plurality of plies of non-metallic, flexible material, secured together face-to-face, each of said plies being provided with transversely extending grooves on one face and permanently expanded portions on the other face, said transverse grooves 110 and permanently expanded portions being opposed to each other on the faces of the respective plies, the combined length of the end portions of the ticket beyond the grooves and expanded portions being of a combined 115 length no greater than the body of the ticket between said grooves and expanded portions, and a non-elastic metallic stiffener located between and extending longitudinally of the plies and crossing the line of 120 the grooves.

2. As an article of manufacture a marking ticket comprising an elongated blank 125 formed of a plurality of plies of flexible non-metallic material secured together face to face, each of said plies being provided at

equal distances from the ends thereof with transverse grooves on one face and correlated expanded portions on the other face, and a non-elastic metallic stiffener extending longitudinally of the plies and crossing said transverse grooves, said metallic stiffener being bent to conform with the said transverse grooves when it crosses the same.

In testimony whereof, I have signed my name to this specification, in the presence 10 of two subscribing witnesses.

GUSTAF A. WALLIN.
